TIE FABRICATION APPARATUS

Morris S. Malek, Ridgefield, N. J.

Application March 14, 1938, Serial No. 195,863

8 Claims. (Cl. 223—1)

This invention relates to tie making machines and methods for the manufacture of ties.

It is within the contemplation of my invention to provide a novel method and machine for fabricating ties wherein the tie material, after being folded upon itself according to a predetermined setting, is temporarily secured together by conventional and inexpensive wire staples in preparation for the final sewing and reversing operations. Certain of the instrumentalities employed in this invention to accomplish the above objectives are disclosed in my three co-pending applications, Serial Nos. 55,970 (which matured on March 15, 1938 into Patent No. 2,110,996), 168,586 and 190,174,—there being certain other devices and expedients described herein which constitute improvements over the methods and apparatus of the said co-pending applications. And in this aspect of my invention, a further object is to enable the use of staples for temporary fastening purpose which may be readily removed before effecting the permanent fastening operation by the application of sewing means.

Among the further objects of my invention are the provisions of a tie making machine capable of speedy one-man operation, and which may be worked by non-skilled operatives having no previous training. It is also another object of my invention to present a simple and inexpensive machine capable of very high productivity.

Still another object of this invention is to enable ties to be rapidly produced without any distortion of the material, whereby ties of presentable appearance can be readily fabricated.

It is also within the contemplation of this invention to efficiently fabricate ties in a manner that will be economical of tie material; and a further object is the provision of facile and speedy adjustments for changes in the shape, texture and thickness of ties and tie material.

Referring to the drawings,

Figure 1 is a front view of the machine containing my invention.

Figure 2 is a side view of said machine.

Figure 3 is an enlarged fragmentary side view of the machine shown partly in section.

Figure 4 is a fragmentary transverse sectional view of a table portion of the machine, illustrating principally the position of the tie material before the folding operation.

Figure 5 is a view similar to Figure 4, showing the position of the parts after the folding operation.

Figure 6 illustrates the form of a driven staple employed by the method of this invention.

Figure 7 is an enlarged fragmentary vertical section similar to that of Figure 5, showing the position of the parts upon the completion of the stapling operation.

Figure 8 is a plan view of the structure of Figure 7.

Figure 9 is a plan view of a portion of a tie illustrating the relative position of lining, outer material and tape after the stapling operation has been completed.

Figure 10 is a fragmentary section of the tie of Figure 9 showing two staples in position.

Figure 11 is a perspective view of one of the brackets for the pivotally mounted holding strips.

Figure 12 is a fragmentary perspective view of the end portion of the pivotal holding strip adapted for attachment to the structure of Figure 11.

Figure 13 is a plan view of one of the holding strips employed in this invention including its pivotal and linear connection to the bracket, and

Figure 14 is a plan view similar to that of Figure 9, showing the relation of the lining, outer material and tape after the parts are temporarily secured together by means of a modified method of stapling.

In the drawings, the main table of the machine of this invention, designated 10, is supported by legs 11. The top of said table has, in the form of my invention shown, three levels, the high or upper level 12, the intermediate level 13, and the lower level 9, said levels being adapted to operatively receive and support certain tie materials and structural elements of the machines as will be hereinafter set forth.

The base plate 14, overlying a substantial portion of the table, slidably supports thereover the plate 15, the guides 16 (see Figure 8) limiting the operative movement of said plate 15 to a forwardly and rearwardly direction. Said plate 15 is provided with a handle 17 adapted to be manually grasped for operatively manipulating the table in a manner to be hereinafter set forth.

The forward part of this structure contains a plurality of gauge elements 18 suitably secured to the upper surface 12 of the plate 15 by means of screw bolts 19. These elements are arranged according to a predetermined setting to conform with the outline of a selected pattern of tie, as is clearly shown in Figure 8.

The rearward portion of the table is provided with another set of gauge elements 20 secured to plate 14 by means of screw bolts 21. Positioned intermediate certain of said gauges 20 are the spring clips 22 yieldably en-

gageable with the upper surface of plate 14. Pivotally secured at 23 to the bracket structures 24 are the body portions of a plurality of stapling machines 25, preferably of conventional structure, 5 each containing a staple magazine 26, a plunger 27, a knob 28, a base 29 and anvil 30. The bases of these machines are suitably supported by the longitudinal structural members 31, 32 and 33, and their connecting parts. As in most conventional 10 stapling machines, the upper body portions thereof are yieldably held in spaced relation to the anvil, as clearly shown in Figure 3. It will be noted that the base plate 14 is provided with apertured portions 34 to expose the anvil 15 30 of each machine to the action of its plunger whereby a driven staple can come into operative engagement therewith.

In overlying relation to the knobs 38 of the 20 row of stapling machines is the beam 35 having secured to the undersurface thereof a plurality of resilient members 36 each of said members being adapted to engage the underlying knob, in a manner to be hereinafter set forth. Suitably connected to said beam 35 are the arms 37 pivotally mounted at 38 of the bracket structure 39. Intermediate the terminals of each of said arms 37 and pivotally connected thereto at 40 is the member 41 to which is secured the rod 42 extending through a suitable aperture in the machine 25 to the treadle 43 near the floor of the structure. Over each of said rods 42 is the helical spring 44 positioned between plates 45 and 46, said spring normally urging the arms 37 and hence the beam 35 upwardly. Said plate 45 is 30 suitably supported by a bracket 47 which is secured in place by the plate 48 and bolts 49.

Pivotally attached to the lateral sides of the table are the two oppositely disposed holding strips 50, each of these being surfaced with a 40 material of substantially high frictional coefficient. In the form shown, the strips are provided with tubular rubber casings 51 clearly shown in Figure 7. These strips have their forward edges of predetermined curvature to conform with the desired shape of the finished tie. 45 The said strips are adapted to be positioned upon the intermediate surface 13, being the upper surface of the plate 14, the distal edges of said strips being in close proximity, and if desired, in actual 50 abutment when the strips are placed in operative engagement and longitudinal alignment on the table, as indicated in Figure 8. It is hence seen that said strips are positioned at a level lower than the aforesaid level 12, for reasons which will 55 hereinafter appear. The pivotal connection for each of said strips comprises a bracket 52 suitably secured to the lateral edge of the table, and a plate member 53 pivotally secured to bracket 52, the tubular lug 54 being operatively positioned 60 between the ears 55 and rotatably secured in place by suitable pins in conventional manner. The upper surface of said bracket is provided with a spring 56 which is in constant engagement with the undersurface of plate member 53 normally urging it and the parts carried thereby upwardly. Each strip 50 is suitably secured to its 65 corresponding plate member 53 by the finger screws 57, the shanks of which extend through two enlarged holes 58 in the terminal portion of said strip. It can at this time be stated that by 70 means of this arrangement, strips of various sizes can be interchangeably employed depending upon the size and shape of tie; and furthermore, the strips can be adjustably manipulated to vary the size and shape of the tie, in a manner that

will be more apparent from the description hereinafter given. Thus, the said strips can be slightly adjusted laterally, and forwardly and rearwardly as shown by the dot-dash lines in Figure 13,—and angularly with reference to the 5 pivotal region at the holes 58. As will be later obvious, any adjustment of said strips 50, in either of the manners aforesaid, will have an effect upon the width and shape of the tie. It should also be observed that due to the action 10 of said spring 56, in the normal position the said strips are retracted from the table, as shown in Figure 1.

In the operation of this device, the lining material 59 is placed upon the intermediate level 15 or plate member 14, the rear edge 60 of said material being placed against and in abutment with the gauge members 20. In performing this operation, the said rear edge of the lining is placed underneath the spring clips 22, which serve to 20 hold said lining in place during the adjustment thereover of the outer material in the manner to be hereinafter set forth. It is understood that said clips 22 are merely auxiliary to this device, and not indispensable, inasmuch as other means 25 may be employed for temporarily holding said lining in place. It will be noted particularly from Figures 4 and 7 that the lining extends forwardly from said gauge elements 20 to a portion of plate 14 intermediate the stapling machines and to gauge elements 18. Thereafter, if 30 it is desired to employ a strip of tape for reinforcing purposes, this is placed upon the lining and in overlying relation to the row of anvils of the stapling machines. It is to be understood 35 that the tape, or even the lining, may be dispensed with without affecting the results effectuated by this device, if such reinforcement is not required or desired.

Thereafter the outer material 61 is placed upon 40 the table, the forward edge 62 of which is placed against the gauge elements 18, the rear portion thereof being in overlying relation to the lining, and extending over the said anvils of the stapling machines. In Figure 8 is illustrated how the 45 outer material 61 is placed against the gauge elements 18, as aforesaid. It is apparent that the placing of the lining, tape and outer material can be effectuated very readily in view of the arrangement of the gauges, inasmuch as the 50 gauge elements 20 are arranged to control the position of the lining and the gauge elements 18 to control the position of the outer material 61.

After the tie materials are positioned in place as above indicated, the holding strips 50 are brought down, by manual manipulation against the action of springs 56, until they come into engagement with the tie material, as shown in Figures 4 and 8. Then the handle 17 is grasped and the plate 15 slidably moved rearwardly, whereupon the arcuate leading edge 63 of the plate 15 will engage the outer material 61 thereabove and fold it over the holding strips 50,—a continued movement of said plate 15 being effective to bring the folded-over portion of the outer material into overlapping engagement with the underlying portion thereof as shown in Figures 5 and 7. At this point the tie materials consisting, in the form illustrated, of the lining, tape and outer materials, are in their proper relative position ready to be temporarily secured together.

With the holding strips 50 being held down in the position shown in Figures 4, 5 and 7, the treadle 43 is depressed, causing a consequent de- 75

pression of the rods 42 and the beam 35 against the action of springs 44. The downward movement of beam 35 obviously carries with it the yieldable elements or equalizers 36 which come into operative engagement with the knobs 28 of the stapling machine, to cause an operative manipulation thereof in conventional manner. In other words, the plunger 27 is depressed, the pivotally mounted body portion of the staple moved downwardly, and a staple forced through two thicknesses of outer tie material, the tape 64 and lining 59. The anvil of the stapling machine is so shaped as to cause the staple legs to be bent outwardly, as clearly illustrated in Figures 6 and 10, the staples 65 containing the legs 66 and 67 clenched outwardly rather than inwardly as in the more customary stapling operation. This form of clinched staple provides a temporary fastening means as is well known in the art where-
by it can be readily removed by grasping it between the fingers and withdrawing it from the material. The yieldable elements 36 are instrumental in causing all the stapling machines to be operatively actuated simultaneously, inasmuch as any difference in distance between the beam 35 and the knobs 28 are taken up by the compression of said equalizers or elements 36.

After the stapling operation has been completed, the holding strips 50 are released, and are obviously urged upwardly by the springs 56 to the position shown in Figure 1, whereupon the tie will assume the position shown by dot-dash lines in this figure. Thereafter the tie is simply grasped at the middle thereof between the terminals of the strips and slidably withdrawn from the strips.

The tie is now in reversed condition, the component parts thereof being suitably secured together by a line of staples 65 as above explained. Thereafter, the tie is taken to an operator who either performs a hand or machine sewing operation. Depending upon the method of manufacture, the staples can be removed either before, during or after the sewing operation is performed. It is preferable in the hand sewing operation for the operator to pull out the staples simultaneously with the sewing operation, which can be readily effectuated without difficulty. After the sewing operation, the tie is put through a simple reversing operation, in accordance with the various modes of practice. By means of the method hereinabove described, it is thus apparent that tie materials can be quickly folded together into their proper relative positions and in accordance with predetermined patterns. No special skill is required inasmuch as the positioning is effectuated by pre-set gauges and the folding accomplished by a simple operation. In order to maintain the materials in such positions until the sewing operation is completed, temporary fastening means are provided by means of the stapling operation above described, which in itself is obviously exceedingly simple to effectuate. It is my contention that although other means of temporarily fastening and holding the tie materials may be employed such as the flexible strips described in my co-pending applications, Serial No. 55,970 and Serial No. 190,174, and the pin setting apparatus described in my co-pending application, Serial No. 168,586, the method constituting the invention herein described has its own distinct advantages, particularly in its ease of operation, simplicity of structure and low cost.

In the slide plate 15 hereinabove referred to, the leading edge 63 is shown to be of arcuate

contour, the preferred arrangement being such that the radius of curvature of edge 63 is greater than that of the forward edges of the holding strips 50. In other words, it is preferred that the distance between the said leading edge and the forward edges of the said holding plates 50 be greater at the central portion of plate 15, than at the ends thereof. With such an arrangement, the end points of the plate, such as those identified by the numerals 68, will contact the tie material and fold it over the holding strips 50 slightly before it will contact and fold the material at the center of the table, thereby effecting a slight plowing inwardly of the tie during the folding operation. This effect is considered desirable, and in any event preferable to a plowing outwardly, which would result if the aforesaid relationship of the said leading edge 63 and forward edges of the plates 50 do not exist. With an outward plowing, a point, which could be identified by the design element B' in Figure 9, would be moved outwardly to the position identified by B'', which would obviously produce distortion of the tie. By the inward plowing, not only is such a distortion obviated, but the row of staples is kept at the center of the lining which obviously is the most preferred arrangement, inasmuch as the line of staples represents substantially the line of stitching at the medial rear portion of the tie.

Another method within the contemplation of this invention for eliminating a possible outward plowing of the material is to arrange the stapling machines convexly with respect to the front of the machine, that is along an arcuate line curved in the reverse direction to the curve of the leading edge 63 of plate 15. This will obviously produce a line of staples slightly along a curved path similar to that shown in Figure 14 where the curvature is illustrated as not being of a very marked degree. When the staples are positioned as shown in Figure 14, it is obvious that there will be a corresponding rearward and inward movement of the end portions of the tie material, so that the edge 69 of the lining and the edge 70 of the outer material will be substantially straight rather than curved as shown in Figure 9, hence not subject to distortion as might occur to material illustrated in Figure 9.

It is of course understood that other additional forms and modifications of the apparatus and adaptations of the method constituting this invention can be employed beyond and in addition to that hereinbefore described, all within the scope of the appended claims.

What I claim is:

1. In a machine for making ties that include an inner lining material and an outer material, a stationary table upon which the said material may be placed, the table containing a movable plate so positioned as to underlie a portion of the outer material whereby upon a manipulation of the plate the outer material will be folded, a plurality of spaced elements extending along a portion of the stationary table for gauging the positioning of the inner lining, a plurality of spaced elements extending along a portion of said movable plate for gauging the positioning of the outer material so that the two materials are in overlapping relation, and stapling means positioned between the two sets of gauging elements for fastening together the folded outer material to the lining material.

2. In a machine for making ties that include an inner lining material and an outer material,

5 a table upon which the said material may be placed, a plurality of stapling devices each having a base, and material holding means coacting with the table for holding the material thereon in place, said table having three levels, the difference between the lowest and middle level being equal to the height of said bases whereby the top of each base is substantially flush with the middle table level, and the difference between the top 10 and the middle levels being sufficient for accommodating said holding means, two layers of the outer material and one layer of the lining material.

15 3. In a machine for making ties, a table, and means for holding the tie material firmly in place on the table, said means comprising a pair of strips pivoted on the said table and formed of a central portion of substantially stiff material covered by a material the outer surface of which 20 is of relatively rough texture whereby said tie material in operative engagement therewith will be frictionally held against movement.

25 4. In a machine for making ties, a table, and means for holding the tie material firmly in place on the table, said means comprising a pair of strips secured to oppositely disposed brackets, said brackets being pivotally secured to the table, each of said strips being adjustably attached to its corresponding bracket for pivotal and 30 linear adjustment with respect thereto.

35 5. The process of forming a tie from an outer material and an inner-lining comprising the steps of positioning the outer material and inner lining in overlapping relation, folding the outer material upon itself, stapling the said materials together, sewing the said materials, and removing the staples.

6. In the process of forming a tie from an

outer material and an inner lining, the steps of positioning the outer material and inner lining in overlapping relation, folding the outer material upon itself over the inner lining, simultaneously inserting a plurality of spaced staples through the two contiguous layers of outer material and the lining at intervals along a substantially longitudinal line of the materials, sewing the said materials and removing the staples.

10 7. In the process of forming a tie from an outer material and an inner lining, the steps of positioning the outer material and inner lining in overlapping relation, folding the outer material upon itself over the inner lining, simultaneously inserting a plurality of spaced staples through 15 the two contiguous layers of outer material and the lining at intervals along a slightly arcuate longitudinal line of the materials, sewing the said materials, and removing the staples.

20 8. In a machine for making ties, a table upon which the tie material is laid, a pair of holding strips over one edge of which the said tie material is adapted to be folded, this edge of the strips being curved substantially in accordance 25 with the outline of the material, and a plate slideable on the said table and which a portion of the tie material is adapted to overlie, said plate being adapted upon a slideable manipulation thereof to fold the said material over the said curved edge of the holding strips, the leading edge of the plate being curved substantially like the curved edge of the holding strips but of a larger radius of curvature, whereby said strips are closer to the end portions of said leading edge than to the 30 middle portion thereof.

35 MORRIS S. MALEK.
